UNITED STATES PATENT OFFICE

148,151

DESIGN FOR A LOUD-SPEAKER CASING

Jay B. Doblin, Laurelton, N. Y., assignor, by
mesne assignments, to Reconstruction Finance
Corporation, Kansas City, Mo., a corporation of
the United States

Application May 10, 1946, Serial No. 129,564

Term of patent 3½ years

(Cl. D26—14)

To all whom it may concern:

Be it known that I, Jay B. Doblin, a citizen of the United States, residing at Laurelton, Queens County, New York, have invented a new, original, and ornamental Design for a Loud-Speaker Casing, of which the following is a specification, reference being had to the accompanying drawings, forming part thereof.

In the drawings, Figs. 1 and 2 are, respectively, a front elevation and a plan view of a loud-speaker casing embodying my new design.

I claim:

The ornamental design for a loud-speaker casing, as shown.

JAY B. DOBLIN.
